US0D1073420S

(12) **United States Design Patent** (10) **Patent No.:** **US D1,073,420 S**
(45) **Date of Patent:** **** May 6, 2025**

(54) **PLANTING DEVICE**

(71) Applicant: **Yajun Ni**, Jinhua (CN)

(72) Inventor: **Yajun Ni**, Jinhua (CN)

(**) Term: **15 Years**

(21) Appl. No.: **29/854,249**

(22) Filed: **Sep. 22, 2022**

Related U.S. Application Data

(62) Division of application No. 29/835,862, filed on Apr. 22, 2022, now Pat. No. Des. 981,809.

(51) **LOC (15) Cl.** **08-03**

(52) **U.S. Cl.**

USPC **D8/8**

(58) **Field of Classification Search**

USPC D8/1, 8, 7, 10

CPC E21B 10/44; E21B 11/005; A01C 5/02;
A01C 5/04

See application file for complete search history.

Primary Examiner — Rachel A. Voorhies

Assistant Examiner — Benjamin D. Wannemacher

(57) **CLAIM**

The ornamental design for a planting device as shown and described.

DESCRIPTION

FIG. 1 is a front and top perspective view of a planting device, showing my new design;

FIG. 2 is a rear and bottom perspective view thereof;

FIG. 3 is a front elevation view thereof;

FIG. 4 is a rear view thereof;

FIG. 5 is a left side elevation view thereof;

FIG. 6 is a right side elevation view thereof;

FIG. 7 is a top plan view thereof; and,

FIG. 8 is a bottom plan view thereof.

1 Claim, 8 Drawing Sheets
